JOHN M. CLARK, OF DETROIT, MICHIGAN, ASSIGNOR TO UNIVERSAL BUTTON FASTENING AND BUTTON COMPANY, OF DETROIT, MICHIGAN, A CORPORATION OF MICHIGAN.

GARMENT LOOP.

Application filed May 13, 1922. Serial No. 560,615.

This invention relates to garment fasteners such as suspender loops or the like.

Among other objects the invention is intended to provide an inexpensive suspender 5 loop or the like which will not lose its shape or efficiency under unusual stress and extended use.

The invention consists in the novel constructions, combinations, and arrangements, 10 to be hereinafter described or claimed, for carrying out the above stated objects and such other objects as will appear hereinafter.

The character of the invention may be best understood by reference to one illustrative device embodying the invention and 15 shown in the accompanying drawing.

In said drawing:

Fig. 1 is an elevation of an overalls suspender loop.

20 Fig. 2 is a section taken along the line 2—2 of Fig. 1.

The device illustrated in the drawing is a loop for connecting the strap of a suspender, such as an overalls suspender, to the front or 25 bib of the overalls. In general it comprises a loop 10 intended to receive the suspender strap 11, illustrated in dotted lines, and a loop 12 intended to receive and retain a button or other suitable fastening. In the present 30 instance, I have illustrated the conventional button fastening, comprising a button 13 usually having a collet or narrowed shank about which the loop engages, which button is secured at a suitable point to the garment. The button is shown in dotted lines 35 secured to the bib 14 of a pair of overalls, also illustrated in dotted lines. It will be understood that one loop for each of the suspender straps is employed on the ordinary 40 overalls. The strap loop 10 is preferably formed of wire of suitable strength bent into an elongated loop to provide a bar 15 about which the strap passes. The end portions of the wire forming the loop 45 are, in general, parallel to the bar 15 and provided with stops 16 at their extremities. In the present instance, these stops are formed by bending the extremities of the wire at an angle, preferably at right angles,

50 to the bar of the loop and arranged to lie, preferably, within the plane of the loop so as not to present any projecting portions upon which clothing might become caught

or torn. Adjacent its extremities the wire is bent slightly out of parallelism with the 55 bar 15 to provide inclined portions 17 which converge toward one another in a direction away from the bar 15. These inclined portions also, preferably, lie within the plane 60 of the loop. If desired, the inclined portions may be offset from the portions 18 of the loop, thus forming shoulders 19. Preferably, the wire forming the loop is sufficiently hardened or spring-like to provide 65 the required strength and resistance to permanent distortion.

The loop 12 is preferably formed of a single piece of wire, the ends of which are bent into eyes or loops 20 which embrace the inclined portions 17 loosely, thereby 70 hinging the button loop to the strap loop. The eyes 20 are preferably located symmetrically with respect to the plane of the loop, and the ends of the wire are bent around so as not to expose any sharp edges on which 75 clothing might become caught or torn.

The loop 12 is further provided with a button-receiving portion 21 sufficiently large 80 to permit the loop to be passed over the head of the button, and a button-retaining portion 22 for retaining the button. The loop is preferably narrowed at 23 so that the passage 24 between the sides is somewhat 85 smaller than the collet or shank of the button to prevent the escape of the button from the retaining part 22. Preferably, the loop 12 is formed of wire which is resilient or 90 spring-like and the receiving part 21 is made slightly smaller than the head of the button, the resilient character of the loop permitting the sides thereof to spring apart, if necessary to receive the button and to permit the shank of the same to pass between the narrowed part 23. After the button is 95 in the lower end of the loop, the sides spring together and retain it in position. Ordinarily, the wire forming the loop 12 need not be of as large a gauge as that forming the loop 10 since means hereafter explained are provided for resisting or combatting stresses 100 tending to distort its shape.

Tensional stresses on the loop, and particularly unusual stress, tend to bring the eyes 20 toward each other by reason of the inclination of the parts 17. Any distortion 105 of the strap loop 10 from its normal shape

tends to increase the inclination of the sides 17, thus increasing the tendency to close the free extremities of the loop 12 together. Thus unusual stresses on the suspender tend 5 rather to preserve the shape of the loop 12 than to distort it or enlarge it so as to decrease its efficiency or permit the button to escape. In many suspender loops heretofore made, unusual stresses tend to separate and 10 permanently distort the parts of the button loop, thus permitting the button to escape.

The stops 16 effectively prevent the loop 12 from becoming detached from the strap loop. The hinging together of the loops 15 permits a degree of flexibility in the connection between the suspender strap and the button not possible with rigidly connected loops, and likewise prevents the button from becoming detached during bending movements of the wearer. Notwithstanding the hinged connection, there are no exposed ends 20 of wire so located as to catch or tear the garment or other clothing.

The device may be made from a minimum 25 amount of wire and by simple operations. Since the action of unusual stress is to preserve the shape of the button loop, it may be made of considerably smaller gauge wire, if desired, because it is not required to 30 possess unusual stiffness. Substantially all of the stresses to which it is subjected are tensional and there are no sharp bends likely to become straightened by the ordinary 35 stresses which it bears.

Obviously, the invention is not limited to any specific form of construction, and the details of the illustrative machine may be variously modified. Moreover, it is not indispensable that all features of the invention 40 be used conjointly; they may be employed advantageously in various different combinations and sub-combinations.

I claim:

1. A device of the class described, comprising 45 in combination, a strap loop formed of a single piece of wire bent into loop form with the end portions thereof inclined to the loop, and a button loop formed of a piece of wire, the ends of which are hinged respectively to said inclined end portion of 50 said strap loop.

2. A suspender loop or the like, compris-

ing in combination, a strap receiving part formed of a piece of wire bent into a loop with the end portions thereof inclined to the 55 general length of the loop and the extremities thereof bent to form stops, and a wire button loop, the ends of which are hinged respectively to said inclined end portions.

3. A suspender loop or the like, comprising 60 in combination, a strap receiving part formed of a piece of wire bent into a loop with the end portions thereof inclined to the general length of the loop and the extremities thereof bent to form stops, and a wire button loop, the ends of which are formed 65 with eyes embracing said inclined portions.

4. A suspender loop or the like comprising 70 in combination, a strap receiving part formed of a piece of wire bent into a loop with the end portions thereof inclined to the general length of the loop and the extremities thereof bent to form stops, and a wire button loop, having a button inserting and 75 button retaining portion, and having the ends thereof formed with eyes to embrace said inclined end portions.

5. A suspender loop or the like comprising 80 in combination a wire strap loop, the end portions of which form one side of said loop and are provided with shoulders and inclined portions having stops at their extremities, and a spring-wire button loop having a button receiving and button retaining portion, and having the ends thereof 85 bent into eyes for embracing said inclined portions.

6. A suspender loop comprising in combination, a strap loop one side of which is discontinuous to provide ends which are free 90 to yield relatively to each other, said loop being constructed and arranged to receive a suspender strap; and an elongated wire button loop the sides and ends of which are 95 spaced apart and having said ends respectively hinged to the free ends of said strap loop so as to be free to move together and apart substantially from normal position, said ends of said strap loop being free to 100 yield in response to the varying downward pull of the button loop.

In testimony whereof, I have signed my name to this specification.

JOHN M. CLARK.
